1,477,681

UNITED STATES PATENT OFFICE.

ARTHUR L. ZWISLER, OF KALAMAZOO, MICHIGAN.

HEATING STOVE AND RADIATOR THEREFOR.

Application filed May 14, 1923. Serial No. 638,849.

To all whom it may concern:

Be it known that I, ARTHUR L. ZWISLER, a citizen of the United States, residing at the city and county of Kalamazoo, State of Michigan, have invented certain new and useful Improvements in Heating Stoves and Radiators Therefor, of which the following is a specification.

This invention relates to improvements 10 in heating stoves and radiators therefor.

My improvements are especially designed for embodiment for use in oil stoves such as are commonly and well-known to the trade as "blue flame" oil stoves which stoves are 15 commonly provided with a chimney and I have illustrated my improvements as embodied or adapted for use in such relation. My improvements are, however, adapted for use in connection with gas plates and 20 other gas burners where it is desired to use the same for heating purposes.

The main object of this invention is to provide an improved heating radiator which is very efficient in the matter of 25 heating capacity, circulating the air and supplying humidity to the heated air.

A further object is to provide an improved heating stove or attachment for oil burning stoves in which the products of combustion 30 are substantially odorless.

Objects pertaining to details and economies of my invention will definitely appear from the detailed description to follow.

I accomplish the objects of my invention 35 by the devices and means described in the following specification. The invention is clearly defined and pointed out in the claims.

A structure which is a preferred embodiment 40 of my invention is clearly illustrated in the accompanying drawing forming a part of this application, in which:

Fig. I is a side elevation of an oil burning heating stove embodying the features 45 of my invention.

Fig. II is a vertical central section through my improved radiator on a line corresponding to line 2—2 of Fig. I.

Fig. III is a plan view of the oil burner 50 stand of the structure illustrated.

Referring to the drawing, I provide in the embodiment of my improvement illustrated an oil burner designated generally by the 55 numeral 1 provided with a chimney 2, the whole being mounted and supported in a stand 3 having a top 4 with a central open-

ing and an annular series of openings for the passage of heat and the products of combustion. My improved radiator is designed to be placed on this stand or when 60 it is removed a cooking utensil may be placed thereon.

My improved radiator comprises a cylindrical base 5 having a downwardly flaring flange 6 adapted to rest upon the top 4 of 65 the stand as indicated. Within this base is an annular water reservoir 7 open at the top, the reservoir being supported on the inwardly projecting flange 8 formed on the upper edge of the lower section or flar- 70 ing portion of the base. This water receptacle is arranged in a spaced relation to the walls of the base providing an annular chamber 9 having an annular series of discharge openings 10 adjacent the top thereof. 75 The annular reservoir provides a central flue or passage 11.

I provide a drum or casing 12 having a downwardly flaring flange 13 at its lower end embracing the upper end of the base 80 member. The top 14 of this casing is provided with a damper 15 so that the heated air and products of combustion may be allowed to escape at the top of the casing if desired. Centrally within the casing is a flue 85 16 telescoping with the upper end of the flue or passage 11 so that the heated air and products of combustion pass upwardly from the burner and are discharged at the top of the casing, a baffle 17 being supported in 90 spaced relation to the upper end of the flue preventing the discharged heated air and products of combustion from impinging directly on the top. When the damper is closed the heated air and products of combustion are compelled to pass downwardly through the drum 12 and are discharged through the openings 10.

I preferably arrange a flange-like baffle member 18 at the lower end of the drum or 100 casing 12 providing a restricted passage 19 around the flue. This brings the current of air in close contact with the side of the flue so that it effectively absorbs the heat therefrom. The water in the reservoir becomes heated so that moisture is added or 105 supplied to the air in the form of vapor and it is found that the structure is practically odorless.

I have illustrated and described my improvements in a very practical embodiment. I have not attempted to illustrate 110

or describe certain modifications or adaptations which I contemplate as I believe the disclosure made will enable those skilled in this art to embody or adapt the same as 5 may be desired.

Having thus described my invention what I claim as new and desire to secure by Letters Patent is:

1. In a heating stove, the combination of 10 a burner provided with a chimney, a stand for said burner provided with a top adapted to receive a radiator, a radiator removably mounted on said top and comprising a base member having an outwardly flaring 15 flange at the bottom thereof adapted to rest on the top of the stand, an annular water reservoir disposed within said base member in spaced relation to the side walls and bottom thereof and providing a surrounding 20 annular chamber and a central passage, said base member having an annular series of discharge openings adjacent its upper edge opening to said annular chamber, a casing having an outwardly flaring flange at the 25 bottom thereof embracing the top of said base member, the top of said casing being provided with a damper, a flue disposed centrally within said casing and adapted to telescope with said passage in said base member when the casing is in position, and a baffle plate disposed above and in spaced relation to the top of said flue whereby when said 30 damper is closed the heated air and products of combustion pass upwardly through the central flue and downwardly at the outside thereof to be discharged through said discharge openings in said base member, said casing having an inwardly projecting annular flange at its lower end disposed in spaced relation to the top of said water receptacle providing a restricted passage from the casing.

2. In a heating stove, the combination of 45 a burner provided with a chimney, a stand for said burner provided with a top adapted to receive a radiator, a radiator removably mounted on said top and comprising a base member having an outwardly flaring flange at the bottom thereof adapted to rest on the 50 top of the stand, an annular water reservoir disposed within said base member in spaced relation to the side walls and bottom thereof and providing a surrounding annular chamber and a central passage, said base 55 member having an annular series of discharge openings adjacent its upper edge opening to said annular chamber, a casing having an outwardly flaring flange at the bottom thereof embracing the top of said base member, the top of said casing being provided with a damper, and a flue disposed 60 centrally within said casing and adapted to telescope with said passage in said base member when the casing is in position, and a baffle plate disposed above and in spaced relation to the top of said flue whereby the 65 heated air and products of combustion pass upwardly through the central flue and downwardly within the casing at the outside of the flue to be discharged through said discharge openings in said base member, said casing having an inwardly pro-

heated air and products of combustion pass upwardly through the central flue and downwardly at the outside thereof to be discharged through said discharge openings in said base member.

3. In a heating stove, the combination with a burner, of a radiator comprising a base member, an annular water reservoir disposed within said base member, said base member having discharge openings at its upper end, a casing mounted on said base member to close the top thereof, a flue disposed centrally within said casing and adapted to coact with said passage in said base member when the casing is in position, and a baffle plate disposed above and in spaced relation to the top of said flue, whereby the heated air and products of combustion pass upwardly through the central flue and downwardly at the outside thereof to be discharged through said discharge openings in said base member, said casing having an inwardly projecting annular flange at its lower end disposed in spaced relation to the top of said water receptacle providing a restricted passage from the casing.

4. In a heating stove, the combination with a burner, of a radiator comprising a base member, an annular water reservoir disposed within said base member providing a central passage, said base member having discharge openings at its upper end, a casing mounted on said base member to close the top thereof, and a flue disposed centrally within said casing and adapted to coact with said passage in said base member when the casing is in position, whereby the heated air and products of combustion pass upwardly through the central flue and downwardly at the outside thereof to be discharged through said discharge openings in said base member.

5. A radiator adapted to be associated with a burner and comprising a base member, an annular water reservoir disposed within said base member in spaced relation to the side walls thereof providing a surrounding annular chamber and a central passage, said base member having an annular series of discharge openings adjacent its upper edge opening to said annular chamber, a casing having an outwardly flaring flange at the bottom thereof embracing the top of said base member, a flue disposed centrally within said casing and adapted to telescope with said passage in said base member when the casing is in position, and a baffle plate disposed above and in spaced relation to the top of said flue whereby the heated air and products of combustion pass upwardly through the central flue and downwardly within the casing at the outside of the flue to be discharged through said discharge openings in said base member, said casing having an inwardly pro-

jecting annular flange at its lower end disposed in spaced relation to the top of said water receptacle providing a restricted passage from the casing.

- 5 6. A radiator adapted to be associated with a burner and comprising a base member, an annular water reservoir disposed within said base member in spaced relation to the side walls thereof providing a 10 rounding annular chamber and a central passage, said base member having an annular series of discharge openings adjacent its upper edge opening to said annular chamber, a casing having an outwardly flaring flange at the bottom thereof embracing the top of said base member, and a flue disposed centrally within said casing and adapted to telescope with said passage in said base member when the casing 15 is in position, whereby the heated air and products of combustion pass upwardly through the central flue and downwardly within the casing at the outside of the flue to be discharged through said discharge 20 openings in said base member.
7. A radiator adapted to be associated with a burner and comprising a base member, an annular water reservoir disposed within said base member providing a central passage, said base member having discharge openings at its upper end, a casing having an outwardly flaring flange at the bottom thereof embracing the top of said base member, and a flue disposed centrally 25 within said casing and adapted to telescope with said passage in said base member when the casing is in position whereby the heated air and products of combustion pass upwardly through the central flue and downwardly within the casing at the outside of the flue to be discharged through said discharge 30 openings in said base member.
- 35 8. A radiator adapted to be associated with a burner and comprising a base member, an annular water reservoir disposed within said base member providing a central passage, said base member having discharge openings at its upper end, a casing having an outwardly flaring flange at the bottom thereof embracing the top of said base member, and a flue disposed centrally within said casing and adapted to telescope with said passage in said base 40 member when the casing is in position whereby the heated air and products of combustion pass upwardly through the central flue and downwardly within the casing at the outside of the flue to be discharged through said discharge 45 openings in spaced relation to the top of said water receptacle providing a restricted passage from the casing.

8. A radiator adapted to be associated with a burner and comprising a base member, an annular water reservoir disposed within said base member providing a central passage, said base member having discharge openings at its upper end, a casing having an outwardly flaring flange at the bottom thereof embracing the top of said base member, and a flue disposed centrally 50 within said casing and adapted to telescope with said passage in said base member when the casing is in position whereby the heated air and products of combustion pass upwardly through the central flue and downwardly within the casing at the outside of the flue to be discharged through said discharge 55 openings in said base member.

9. A radiator adapted to be associated with a burner and comprising a base member, an annular water reservoir disposed within said base member providing a central passage, said base member having discharge openings at its upper end, a casing having an outwardly flaring flange at the bottom thereof embracing the top of said base member, the top of said casing being provided with a damper, and a flue disposed centrally within said casing and adapted to telescope with said passage in said base 60 member when the casing is in position whereby when said damper is closed the heated air and products of combustion pass upwardly through the central flue and downwardly within the casing at the outside of the flue to be discharged through said discharge 65 openings in said base member.

In witness whereof, I have hereunto set my hand.

ARTHUR L. ZWISLER. [L.S.]
